COMBINATION TABLE AND BENCH

James E. Garland, Miami, Fla.

Application March 3, 1955, Serial No. 491,865

5 Claims. (Cl. 155—43)

This invention relates to new and useful improvements in articles of furniture and the primary object of the present invention is to provide a combination table and bench having novel and improved features over that disclosed in my co-pending application, Serial Number 421,913, filed April 8, 1954, now Patent No. 2,711,208, granted June 21, 1955.

Another important object of the present invention is to provide a combination table and bench particularly adapted for use in schools and which table and bench is so designed as to be conveniently and comfortably employed by children of various sizes as well as adults.

Yet another object of the present invention is to provide a combination table and bench including an upper structure that forms the table top and seat portion and which upper structure may be selectively retained in a seat forming or table top forming position.

A further object of the present invention is to provide a combined table top and seat structure of the aforementioned character embodying novel and improved means for locking the upper structure in either a seat forming or table forming position.

A still further aim of the present invention is to provide a combined table and seat structure that is so designed as to afford maximum stability while arranged in either a table or seat forming position and which structure also offers the maximum seating comfort for a plurality of children.

These and other objects and advantages of the invention will be apparent upon reading of the subjoined description in connection with the accompanying drawings in which:

Figure 1 is a perspective view of the present invention assembled as a table structure;

Figure 2 is a perspective view of the present invention assembled as a bench structure;

Figure 3 is an enlarged detailed vertical sectional view taken substantially on the plane of section line 3—3 of Figure 2;

Figure 4 is an enlarged detailed vertical sectional view taken substantially on the plane of section line 4—4 of Figure 2; and

Figure 5 is a view similar to Figure 4 but showing the locking mechanism in modified form.

Referring now to the drawings in detail, wherein for the purpose of illustration, there is disclosed a preferred embodiment of the present invention, the numeral 10 represents the base or lower structure generally, and the numeral 12 represents the upper structure generally.

The base structure 10 is composed of a pair of vertically disposed end members 14 and 16 that are connected together by a horizontally disposed center beam 18. The ends of the beam 18 are preferably suitably secured within sockets or holding wells 20 and 22 integrally formed with the opposing inner faces of the end members 14 and 16.

End members 14 and 16 are preferably formed of

metal and are substantially inverted T-shaped in configuration to include bearing feet 24, 26 and 28, 30. The feet 24 and 26 of the end member 14 project an equal distance from opposite sides of the vertical axis of the member 14 and the feet 28 and 30 of member 16 project an equal distance from opposite sides of the vertical axis of the member 16, it being understood that members 14 and 16 are identical in construction and size.

The upper end portions of the end members 14 and 16 terminate in cylindrical portions 32 and 34 having inwardly facing peripheral rims 36 and 38, and central hub portions 40 for a purpose which will later be described in detail.

Upper structure 12 is actually a table top 46 and seat panel 44 which are joined at a slightly obtuse angle. A pair of upper end members 48 and 50 are fixed to the ends of the panel 44.

The outer free end portions of the upper end members 48 and 50 terminate in cylindrical portions 52 and 54 having peripheral rims on flanges 56 and 58. The portions 52 and 54 are also provided with integral hub portions 62 that abut the hub portions 40 of the previously referred to cylindrical portions 32 and 34.

The abutting portions 40 and 62 are centrally horizontally apertured to accommodate pivot bolts 64. In this manner the upper structure 12 is pivotally secured to the base structure 10 while horizontal shifting of the upper structure relative to the lower structure is prevented due to hub portions 40 abutting hub portions 62 and further by rims 36 and 38 engaging rims 56 and 58.

Means is provided for locking the upper structure 12 relative to the lower structure 10 so that the entire article may be employed as a table as shown in Figure 1, or as a bench as shown in Figure 2. This locking means comprises a horizontally disposed rotatable, locking shaft 68 having its end portions rotatably positioned in horizontal apertures 70 in the end members 14 and 16 below the cylindrical portions 32 and 34. The end portions of the locking shaft 68 are provided with multi-sided recesses 72 to accommodate a key or tool for rotating the shaft.

Substantially C-shaped locking dogs 74 are pivotally secured by pivots 76 at one of their ends to the end members 14 and 16. The ends of the dogs 74 remote from the pivots 76 terminate in vertical portions 78 whose lower reduced ends 80 pass vertically downwardly through guide sleeves 82 suitably fixed to or formed with the end members 14 and 16. The lower reduced ends 80 are threaded to receive nuts 84 that limit upward movement of the end portions 78. Coil springs or resilient members 86 are biased between the shouldered parts 88 of the portions 78 and the sleeves 82 to yieldingly urge the portions 78 upwardly against the rims 56 and 58 of upper end members 52 and 54.

Cams or eccentrics 90 are suitably fixed to the end portions of shaft 68 and ride against the concave surfaces 92 of the locking dogs 74 as the shaft 68 is rotated by the proper tool placed in one of the recesses 72 at the ends of shaft 68.

The rims 56 and 58 are provided with peripherally spaced recesses or detents 92 and 94, the recesses 92 being so located as to receive the upper ends of the portions 78 when the structure 12 is rotated to form a table (Figure 1), and the recesses 94 are so located as to receive the upper ends of the portions 78 when the upper structure is rotated to form a bench in conjunction with the base structure (Figure 2).

Figure 5 illustrates the locking mechanism in slightly modified form wherein the locking dogs 74a are pivoted to the end members 14 and 16 and overlie cams or eccentrics 90a fixed to the ends of shaft 68a.

Suitably fixed to the ends of shaft 68a are radially disposed arms 91a that are suitably connected to the upper ends of coil springs 93. The lower ends of the springs 93 are suitably secured to the end members 14 and 16 and yieldingly urge the lobes of the cams 90a against the dogs 74a. The shaft 68a may be manually rotated against action of the springs 93 so that the dogs 74a may gravitate out of locking engagement with the upper end members of the upper structure.

It is observed that the present invention comprises a structure wherein the panel 44 will be disposed below the pivots 64 when the device is arranged to form a bench inasmuch as this arrangement affords maximum stability. Also, the pressure or bearing feet 24, 26, 28 and 30 are disposed equidistant from the vertical axis of their associated end members which axis the pivots 64 intersect to promote increased stability.

The top 46 must be from 28 to 31 inches in height for proper seating thereto. The panel 44 when disposed as a seat portion must be disposed between the limits of 14 inches for smaller grade children to 18 inches for adults. This height allows the feet to rest comfortably on the floor, yet allows the weight of the body to press directly down on the chair through the buttock rather than through the upper legs.

The table top 46 should be between 29 and 32 inches in width for proper use of the article of furniture as a table as well as a bench.

It is observed that seat forming panel 44 may be positioned with respect to the pivots 64 at the time of construction without disturbing the remainder of the structure disclosed. However, since the pivots 64 will be located at a maximum of 20 inches above floor level the seat forming panel 44 will always be disposed below the pivots 64 for proper and necessary stability. Furthermore, it will be noted from Figure 4 that the top 46 may abut the end members 14 and 16 inwardly of the feet 26 and 30 to further add to the stability of the combination table and bench when the same is arranged in its bench forming position.

Having described the invention, what is claimed as new is:

1. A combination bench and table comprising a base structure including a pair of spaced parallel interconnected vertically disposed end members each having a pair of bearing feet, an upper structure including a pair of relatively inclined panels fixed together and defining respectively a table top and a seat portion, a pair of upper end members fixed to the table top of said upper structure and having end portions overlapping the end members of said base structure, coaxial horizontal pivots connecting the end members of the upper structure to the end members of the base structure and means interconnecting the base and upper structures for locking the table top in either a horizontal or a vertically inclined position, said locking means comprising a spring urged locking dog, and cams engageable with said dogs to urge the dogs out of locking position.

2. A combination bench and table comprising a base structure including a pair of spaced parallel interconnected vertically disposed end members each having a pair of bearing feet, an upper structure including a pair of relatively inclined panels fixed together and defining respectively a table top and a seat portion, a pair of upper end member fixed to the table top of said upper structure and having end portions overlapping the end mem-

bers of said base structure, coaxial horizontal pivots connecting the end members of the upper structure to the end members of the base structure and means interconnecting the base and upper structures for locking the table top in either a horizontal or a vertically inclined position, said locking means comprising a pair of spring urged locking dogs movable into and out of engagement with said upper end members, and manually actuatable cams engageable with said dogs to move the latter out of engagement with said upper end members.

3. A combination bench and table comprising a base structure including a pair of spaced parallel interconnected vertically disposed end members each having a pair of bearing feet, and upper structure including a pair of relatively inclined panels fixed together and defining respectively a table top and a seat portion, a pair of upper end members fixed to the table top of said upper structure and having end portions overlapping the end members of said base structure, coaxial horizontal pivots connecting the end members of the upper structure to the end members of the base structure and means interconnecting the base and upper structures for locking the table top in either a horizontal or a vertically inclined position, said locking means comprising a pair of spring urged locking dogs carried by the base structure end members and movable into and out of engagement with said upper end members, a horizontally disposed shaft rotatably supported by said base structure end members, cams fixed to said shaft and engageable with said dogs to urge the latter out of engagement with said upper end members.

4. A combination bench and table comprising a base structure including a pair of spaced parallel vertically disposed end members, each of said end members having a pair of bearing feet, an upper structure including a pair of relatively inclined panels rigidly secured together and defining respectively a table top and a seat portion, said table top having an undersurface and said seat portion having an upper seating surface, a pair of upper end members rigidly secured to the underside of said table top, said upper end members overlapping the end members of said base structure, coaxial horizontal pivots connecting said upper end members to the end members of said base structure, said pivots lying within the angle defined by the upper seating surface of said seat portion and the underside of said table top, whereby said seat portion, when in a horizontal seat forming position, is disposed below the axis of said horizontal pivots, and cooperating latch means on said end members of said base structure and said upper end members interconnecting the base and upper structures for locking said upper structure in either a table forming position or a bench forming position.

5. The combination bench and table of claim 4 wherein in said table top and said seat portion define the complete seating surface.
